NOTATION-PRINTING DEVICE

Oscar J. Sundstrand, Rockford, Ill., assignor, by
mesne assignments, to Underwood Elliott
Fisher Company, New York, N. Y., a corpora-
tion of Delaware

Application October 9, 1930, Serial No. 487,399

23 Claims. (Cl. 101—93)

This invention relates to computing and printing machines, and particularly to means for printing notations or memoranda alongside an item when desired. The invention aims to provide means for this purpose which shall be capable of printing a considerable variety of notations, which shall permit of printing notations either at the right-hand or left-hand side of the item, which shall be conveniently operable, which shall be relatively inexpensive, and which shall be in the nature of a self-contained unit which may be readily incorporated in a machine of the class referred to.

In the accompanying drawings:

15 Figure 1 is a fragmental front elevation of a computing and printing machine embodying the features of my invention.

Fig. 2 is a fragmental plan view of the machine.

20 Fig. 3 is a fragmental right-hand elevation.

Fig. 4 is a section on line 4—4 of Fig. 5.

Fig. 5 is a section on line 5—5 of Fig. 2.

I have herein shown the invention as embodied in a machine of the general type disclosed in the 25 Sundstrand Patents Nos. 1,198,487 and 1,759,069, but it should be understood that the invention is applicable to machines of other types.

The means for supporting the work-piece or pieces may be of any desired character, as, for 30 example, a laterally shiftable rotary platen. For the sake of simplicity I have herein shown a single work-piece consisting of a wide sheet *a*. The ink ribbon is indicated at *b*.

35 3 are the vertically reciprocatory type bars for printing the items and totals. They are arranged in a compact group, as shown in Fig. 2. As will be understood from Fig. 3, the type bars are normally about one step below the printing line or horizontal plane in which printing is done on the 40 paper.

The means for printing memoranda upon the work-piece *a* comprises a base plate 4 which is secured to the top of the case 5 by means of screws 6 and to the sides of the case by means of screws 45 6^a. The opposite ends of the base plate 4 carry upwardly extending flanges 7 to which are secured two parallel guide rods 8 extending transversely of the machine. A frame 9 is slidably mounted on the guide rods 8 so as to be movable laterally of the machine in front of and adjacent to the platen 2. In the frame 9 are mounted type-carrying plungers 10 arranged in parallel relation to each other and in a plane. These 50 plungers are slidably mounted in the frame 9 so as to be adapted to reciprocate toward and away

from the platen, the frame 9 being mounted in an inclined position so that the plungers 9 are directed toward the printing line. Each plunger 10 has fixed to its forward end a type 11 adapted to imprint a certain notation on the work-piece. 60 These notations will vary with the character of the business in which the machine is to be employed, and the notations which the various type are adapted to print may be visually indicated by means of inscriptions or labels 12 mounted on the front of the frame 9, as shown in Fig. 1. Each plunger 10 is normally held in retracted position by means of a coiled spring 13 which is stretched between an anchor post 14 on the plunger and a 65 rod 15 secured in the frame 9.

70 Means is provided whereby a selected plunger 10 may be driven into contact with the ribbon *b* to make an imprint upon the work-piece *a* at either the right-hand or the left-hand end of an item. The means herein shown for this purpose is in duplicate, one device being adapted to cause printing at the right-hand end of the item and the other at the left-hand end of the item. In the form herein shown, each of said means 75 comprises an upwardly extending arm or driver 16 fixed upon one end of a rock shaft 17 which is journaled in downwardly extending flanges 18 and 19 on the forward portion of the base plate 4. To the other end of the rock shaft is 80 fixed a crank arm 20 which is normally held against a stop pin 21 by means of a coiled spring 22. Said spring is anchored at 23 on the flange 19 and is connected to a pin 24 on the crank arm 20. A key lever 25 is pivoted intermediate 85 its ends at 26 on the flange 19. One arm of said lever has a slot 27 to receive the pin 24. The other end of the key lever bears a key 28.

90 One of the arms 16 is located to swing in a vertical plane extending longitudinally of the machine at the right-hand side of the group of type bars 3. The other arm 16 is arranged to swing in a similar plane located adjacent to the opposite side of the group of type bars. It will be seen that by sliding the frame 9 to bring the desired plunger 10 into the plane in which the right-hand arm 16 swings, the desired notation may be printed upon the work-piece at the right-hand side of the place where an item is about to be printed, and that by sliding the frame 9 to bring a desired plunger into the plane in which the left-hand arm 16 swings, an appropriate notation may be printed at the left-hand side of the place on the work-piece at which an item 95 is to be printed. For convenience in thus shifting 100 the frame 9, the frame 9 is provided with a 105 handle 29 which is secured to the frame 9.

110

ing the frame 9 upon the guide rods 8, a knob 29 is secured to said frame.

As will be understood from Figs. 3 and 5, the lowered position occupied by the type bars 3 when the latter are idle affords clearance above the type bars to permit the type plungers 10 to be driven against the printing line. As shown in Fig. 2, the left-hand arm 16 may be located so as to produce an imprint in the vertical plane 10 of the type bar 3 farthest to the left or the one next thereto, these type bars in practice being generally used only in printing totals.

For convenience in accurately locating the frame 9 with the desired type plunger 10 in alignment with the desired arm 16, I provide a bar 30 secured to the base plate 4 and extending transversely of the machine below the path of movement of the frame 9. The rear edge of the bar 30 has a series of notches 31 spaced to correspond to the various operative positions of the frame 9. To said frame is pivoted at 32 a lever 33 that carries at one end a roller 34 adapted to engage in the notches 31. A coiled spring 35 stretched between the opposite end of the lever 33 and an anchorage 36 on the frame 9 presses the roller 34 against the notched bar 30. It will be seen that the roller 34 will yield to allow the frame 9 to be slid into the desired position, such position being accurately determined by engagement of said roller with one of the notches 31.

In use, the operator slides the frame 9 into position to print a notation describing the item about to be printed, after which the operator taps the key 28 to drive the selected type-carrying plunger 10 against the ribbon, the plunger being promptly withdrawn by its spring 13. The operator then sets up the item on the keyboard of the machine and puts the machine through its cycle of operations by pulling the handle or depressing the motor bar.

It will be seen that the frame 9 may be made of any desired width to support any desired number of type-carrying plungers and that the invention consequently is adapted to provide a relatively large assortment of notations.

While I have herein shown duplicate means for actuating the type-carrying plungers whereby notations may be printed at either end of the item, it will be understood that the invention may be embodied in a machine having means for printing at one end only of the item.

In Patent No. 1,759,069 above referred to the two type bars farthest to the left are utilized for printing symbols, dates and other notations. It will be seen by means of the construction herein shown the notation-printing means disclosed in said patent may be dispensed with, thus releasing the two type bars farthest to the left for use in printing numerals.

It will be noted that the platen and the auxiliary group of type-carrying members 10 are movable independently of each other and laterally of the group of type bars, hence any desired notation provided for by the plungers 10 may be printed in any column on the work-piece or pieces.

I claim as my invention:

1. A printing machine having, in combination, a platen, a group of type bars in front of the platen, said type bars normally occupying a position about one step below the printing line on the platen, stationary guide means in front of the type bars and extending parallel with the platen, two drivers pivotally supported in front

of said guide means to swing in vertical planes extending longitudinally of the machine, one of said planes extending along one end of the group of type bars and the other adjacent to the other end of said group of type bars, two key levers each arranged to operate one of said drivers, a frame slideable upon said guide means, a plurality of type-carrying plungers mounted in said frame in parallel relation to each other and directed toward the printing line on the platen, individual springs normally holding said plungers in retracted position, said frame being laterally slideable on said guide means to bring any selected plunger into the field of action of either of said drivers, and yieldable means for accurately locating said frame in its adjusted position.

2. A printing machine having, in combination, a platen, a group of type bars adjacent to the platen, stationary guide means extending parallel with the platen, a driver pivotally supported in front of said guide means to swing in a vertical plane extending longitudinally of the machine and along one end of the group of type bars, a key lever arranged to operate said driver, a frame slideable upon said guide means, a plurality of type-carrying plungers mounted in said frame in parallel relation to each other and directed toward the printing line on the platen, means normally holding said plungers in retracted position, said frame being laterally slideable on said guide means to bring any selected plunger into the field of action of said driver, and yieldable means for accurately locating said frame in its adjusted position.

3. A printing machine having, in combination, a platen, a group of type bars in front of the platen, said type bars normally occupying a position about one step below the printing line on the platen, stationary guide means in front of the type bars and extending parallel with the platen, a driver pivotally supported in front of said guide means to swing in a vertical plane extending longitudinally of the machine and along one end of the group of type bars, a key lever arranged to operate said driver, a frame slideable upon said guide means, a plurality of type-carrying plungers mounted in said frame and directed toward the printing line on the platen, said frame being laterally slideable on said guide means to bring any selected plunger into the field of action of said driver, and yieldable means for accurately locating said frame in its adjusted position.

4. A printing machine having, in combination, a platen, a group of type bars in front of the platen, said type bars normally being below the printing line on the platen, two drivers movable in vertical planes extending longitudinally of the machine, one of said planes extending along one end of the group of type bars and the other adjacent to the other end of said group of type bars, two key levers each arranged to operate one of said drivers, a frame carrying a plurality of type-carrying plungers directed from a plane above the type bars toward the printing line on the platen, and individual springs normally holding said plungers in retracted position, said frame being movable to bring any selected plunger into the field of action of either of said drivers.

5. In a printing machine, the combination of a platen, a group of type bars arranged to print upon the platen, a group of notation-printing type-carrying members arranged in parallel relation to each other and shiftable laterally to position a selected type-carrying member at one

side of the group of type bars, and means for actuating the positioned type-carrying member.

6. In a printing machine, the combination of a platen, a group of type bars arranged to print upon the platen, a group of notation-printing type-carrying members shiftable laterally to position a selected type-carrying member at either side of the group of type bars, and means for actuating the positioned type-carrying member.

10 7. In a printing machine, the combination of a platen, a group of type bars arranged to print upon the platen, a group of notation-printing type-carrying plungers arranged in a plane, the group being laterally shiftable in said plane to position a selected type-carrying plunger at one side of the group of type bars, and means for actuating the positioned type-carrying plunger.

8. The combination of an elongated paper-carrying platen, a driver, and a group of parallel type-carrying plungers operatively mounted externally of, and shiftable longitudinally with respect to said platen to place a selected plunger within the field of action of said driver, all of said plungers being directed toward the printing line on the platen.

25 9. The combination of an elongated rotary platen, a digitally operable driver, and a group of type-carrying plungers shiftable axially of said platen to place a selected plunger within the field of action of said driver, said plungers being directed toward the printing line on the platen.

10. The combination of a platen, a group of type bars normally below the printing line on the platen, a laterally shiftable group of parallel type-carrying members located in a plane above the type bars, said plane being inclined, whereby said members are directed toward the printing line, and means to actuate the type-carrying members.

40 11. In combination with a printing machine having a platen and a group of type bars arranged to print upon the platen, a notation-printing attachment comprising a base plate, guides supported by said base plate, a frame slidably mounted on the guides, printing devices in said frame, and a digitally-operable member carried by said base plate for actuating said devices.

12. In a printing machine, the combination of a platen, a plurality of groups of printing elements arranged to print on a common line on said platen, and means to reverse the relative order in which said groups are arranged to print on said line.

55 13. In a printing machine, the combination of a platen, two groups of printing elements arranged to print in a common continuous line on said platen and means to position one of said groups to print in juxtaposition to the first group in prefixing or appending relation.

60 14. In a printing machine, the combination of a platen, two groups of printing elements arranged to print on a common line on said platen, means to effect relative lateral movement between said groups to determine the order in which they shall print, and means to actuate said elements.

15. In a printing machine, the combination of a platen, a group of printing elements arranged for line printing on said platen, a second

group of printing elements arranged for printing on the same line, and means to shift said second group of printing elements into position to precede or follow said first group.

16. In a printing machine, the combination of a platen, a group of type bars arranged for line printing upon said platen, and a group of notation-printing type-carrying members also arranged for line printing, said notation printing members being shiftable relative to said group of type bars to prefix or append the line printed thereby.

17. In a printing machine, the combination of a platen, and two groups of printing elements arranged to print in a common line on the platen, said groups of printing elements being relatively shiftable to cause the imprints of one to precede or follow the imprints of the other.

18. The combination of a cylindrical platen, a group of type bars normally below the printing line on the platen, a laterally shiftable group of parallel, type-carrying members located in a plane which is above the normal position of the type bars and which intersects the platen, and means to actuate the type-carrying members.

19. The combination of a cylindrical platen, a group of vertically reciprocatory type bars which are normally below the printing line on the platen, a laterally shiftable group of type-carrying members located above the normal position of the type bars, and means to actuate said type-carrying members.

20. The combination of a group of type bars for printing amounts, a platen to receive impressions from said type bars, and other printing means also adapted to coact with the platen and movable laterally to either side of the group of type bars to prefix or append the line of printing of said type bars.

21. A printing machine having in combination an elongated cylindrical platen, a group of parallel type carrying members shiftable longitudinally of the axis of the platen to position a selected type carrying member, said type carrying members being arranged for operation in a plane which intersects the platen to define a segment thereof, and a group of type bars adapted to be positioned for operation in a plane common to the axis of the platen which plane intersects the plane of the type carrying members in a line common to the surface of the platen.

22. A printing machine having in combination, a cylindrical platen, a group of printing means arranged for operation in a plane common to the axis of the platen to effect imprints on a line on the surface of the platen, and a second group of printing means arranged for operation in a plane angularly disposed to the plane of operation of said first mentioned group to effect imprints on the same said line.

23. A printing machine having in combination, a platen, a group of coplanar printing means arranged to effect imprints on a line on the surface of said platen, and a second group of printing means arranged for operation in a plane angularly disposed to the plane of operation of said first mentioned group of printing means to effect imprints on the same line on said platen.

OSCAR J. SUNDSTRAND.
